HINGED SKI

Robert Beaton Smith, Santa Monica, Calif.

Application November 12, 1941, Serial No. 418,808

12 Claims. (Cl. 280—11.13)

This invention is a novel improvement in folding skis, in which the ski is provided with hinged sections which will permit the ski to be readily and conveniently folded in such manner that the front and rear sections when folded will be disposed substantially parallel, and folded ski being approximately half the length of the normal ski. Ordinary skis are generally about seven feet in length; and the inconvenience of transporting same because of their length is well known, said length preventing same from being carried inside the usual automobile body, and rendering same inconvenient for shipping by train or the like due to the fact that they require a special rack, or must be crated to prevent breakage.

The principal objects of my invention are to provide a ski having a hinge of minimum weight, and of inexpensive construction, which hinge is simple to operate since the necessity of using a wrench, screw driver or other tool in order to make or break the lock in folding and unfolding the ski is not required; also a hinged ski in which the two hinged sections thereof cannot come apart in that no parts of the hinge itself may become disassembled; also to provide a hinge for a ski which will not reduce the strength of the ski, and a hinge which therefore may be disposed at or near the center of the ski without sacrificing the strength of the ski, the weakest part of the normal ski being at a point some distance ahead of the center of the ski; also to provide a ski hinge and lock in which the front and rear members of the hinge will be held in rigid alignment with respect to each other when the members are locked in such position; to provide a ski hinge in which the lock is adapted to take up any play or looseness between the members thereof which may arise due to wear or to manufacturing tolerance; and further to provide a hinged ski in which the running surface thereof will constantly remain smooth.

I will explain the invention with reference to the accompanying drawings, which illustrate one practical embodiment thereof to enable others familiar with the art to adopt and use the same; and will summarize in the claims, the novel features of construction, and novel combinations of parts, for which protection is desired.

In said drawings:

Fig. 1 is a perspective view of adjacent sections of a ski connected together by my novel hinge, showing the sections in normal aligned position.

Fig. 2 is a perspective view thereof showing the sections of the ski in folded position.

Fig. 3 is a perspective view of one of the hinges, detached, showing the members thereof in unlocked and disaligned position.

Fig. 4 is an elevation of the hinge, detached, showing in full lines the members in aligned and locked position, and showing in dotted lines one member of the hinge in fully folded position, and showing in dot-and-dash lines one member of the hinge in an intermediate folded position.

10 Fig. 5 is a transverse section on the line 5—5, Fig. 4.

As shown in Figs. 1 and 2, the ski is provided with a front section F, and a rear section R, which in normal position are in abutting relationship, said sections having complementary beveled ends F' and R' cut at an angle of approximately 60° with respect to the horizontal plane, although the angle may be varied, the beveled ends F' and R' permitting the sections 15 F and R to be readily folded and making possible the use of my novel locking hinge, and further allowing the running surface of the aligned sections to be kept smooth with no appreciable gap therebetween.

25 At each side of the ski, bridging the abutting ends of the ski sections F and R, is a hinge which consists of a pair of channel-shaped members 1 and 2 made preferably of chrome molybdenum steel, heat treated to a high tensile strength of 30 approximately 150,000 pounds per square inch. Members 1 and 2 are adapted to abut in aligned relation as shown in Figs. 1 and 4, the abutting ends of the channels being beveled, as at 1a, 2a (Fig. 1), at the same angle as the abutting ends 35 F', R' of the ski sections so that when the members 1 and 2 are mounted at the sides of the ski sections F and R the beveled ends 1a, 2a will be disposed directly opposite the beveled ends F', R' of the ski sections. Preferably the hinge is disposed adjacent the center of the ski so as to locate the foot binding (not shown) which holds 40 the toe of the ski boot to the ski about two inches behind the center of the hinge; but the hinge may be disposed in any other desired position.

45 In the bosom of the channel members 1 and 2 are additional web members 3 and 4 shown more particularly in Figs. 3 and 4, the same being preferably welded to the upper and lower flanges of the channel members 1 and 2 as indicated, the 50 additional webs 3 and 4 being spaced approximately one-eighth of an inch from the webs of the channel members 1 and 2 and parallel therewith. The inner ends of the webs 3 and 4 are also beveled as at 3a, 4a parallel with and opposite the beveled ends 1a, 2a of the channel mem-

bers 1 and 2. Housed within the spaces between the webs of channels 1 and 2 and the additional webs 3 and 4 is a link 5 having its lower edge normally disposed flush with the lower surface of the lower flanges of the channel members 1 and 2, as indicated in Fig. 4, the ends of the link 5 being perforated to receive bolts or rivets 6 and 7 in double shear which transfix the webs of the channel members 1 and 2 and the additional webs 3 and 4, the ends of the bolts or rivets being enlarged to prevent same from dropping or backing out of their holes in the channels and webs. The lower flanges of channel members 1 and 2 are slotted inwardly as at 8 (Fig. 2) to points beyond the bolts or rivets 6 and 7 to permit link 5 to swing freely on its pivots 6 and 7. Link 5 thus permits the channel member 1 to be swung downwardly, around and under the channel member 2, as indicated in Fig. 4.

If desired, an aligning tongue 9 may be secured between the web of channel 1 and the additional web 3 thereof adjacent the upper flange of channel 1, said tongue being adapted to enter between the web of channel 2 and its additional web 4 when the members 1 and 2 are in normal aligned position. However, the tongue 9 is not essential and may be omitted.

The upper flange of the channel member 2 adjacent the beveled end 2a is somewhat widened as at 2c, and carries on its upper surface a wedge-shaped plate 10 thickest at its outer end, said plate 10 having a longitudinal slot 10a therein extending inwardly from its outer end. Welded on the additional web 3 of the channel member 1 is a bolt 11, the axis of which crosses the line of bevel of the ends 1a and 3a of channel member 1, said bolt extending above the upper flange of the channel 1 and being adapted to enter the slot 10a in beveled plate 10 of channel 2, said bolt 11 carrying a thumb or wing nut 12 or the like, adapted when the parts are in normal position shown in Figs. 1 and 4 to be screwed down without the aid of a wrench or other tool to seat upon the wedge plate 10 and thereby lock the channel members 1, 2 in aligned position, the base of nut 12 seating squarely upon the top of the bevel plate 10. The outer end of bolt 11 is enlarged to prevent nut 12 from becoming disengaged with the bolt. By the above construction, the bolt 11 welded to the additional web 3 and carrying the wing nut 12, and the slotted plate 10, constitute the lock of the hinge.

Each hinge unit is secured on the side edge of the ski sections F and R by screws 13 or the like, three being shown on each member 1 and 2, passing through holes provided therefor in the webs of the channels 1 and 2 and through the additional webs 3 and 4. The bosom of the channel members 1 and 2 snugly receive the sides of the ski sections F and R which may be recessed to receive the channel members 1 and 2, so that the outer faces of the channel flanges and web lie flush with the tops, sides and bottoms of the ski sections; and as previously stated the hinge members are so mounted that the beveled ends of the channels 1 and 2 are disposed directly opposite the beveled end F' and R' of ski sections F and R.

In order to fold the ski, the wing nuts 12 must be sufficiently unscrewed or loosened, and then the front section F and channel members of the hinge are free to rotate about rivet or pin 6. When thus rotated approximately 90° or into the position shown in dot-and-dash lines in Fig. 4, further rotation can take place about pin 7, or

into position shown in dotted lines in Fig. 4; and the corner of channel 1 will clear the bottom of channel 2. Correspondingly, when the hinge is straightened out, one quarter turn must first take place around pin 7 and then a second quarter turn about pin 6, or until the hinge is straight.

The fact that the hinge channels are beveled on a diagonal (about 60° in this case) is an essential feature in the design, as it makes two features possible; first, it allows the running surface of the ski to be kept smooth with no appreciable gap between the sections F and R, and also permits the ski to fold; and second, it makes the lock possible, as that when the wing nut 12 is tightened, the front and rear halves of the ski and hinge are pulled together, and the front halves tend to slide upwardly with respect to the rear halves until they are in contact along the full length of the diagonal cut, thus holding the front and rear halves in alignment at all times. Also, as the pins 6 and 7 or links 5 may wear somewhat due to use, the play will be taken up by the front halves sliding up a little further than normally, but the correct alignment of the ski sections will still be maintained. Since the wing nut lock is disposed on the upper surface of the hinge, the lock does not interfere in any way with the installation of the ski boot binding.

I do not limit my invention to the exact form shown in the drawings, for obviously changes may be made therein within the scope of the claims.

I claim:

1. A ski comprising runner sections having their adjacent ends adapted to abut in a transverse plane disposed at an angle to the plane of the aligned section; hinge units connecting the sections; each unit including a pair of members secured to the respective sides of the sections and adapted to abut in the plane of the ends of the sections, a link having its ends pivoted to the respective members of the pair whereby the sections may be swung from alignment into spaced parallel relation, and means on the members for locking same in abutting position, said locking means comprising a slotted flange at the upper edge of one member; a projection on the other member crossing the beveled end thereof and extending above the upper edge thereof and adapted to enter the slot in the flange when the members are aligned; and means on said projection adapted to engage the top of said slotted flange.

2. A ski comprising front and rear runner sections having their adjacent ends adapted to abut in a transverse plane disposed at an angle to the plane of the aligned sections; hinge units connecting the sections; each unit including a pair of channel members secured to the respective sides of the sections and adapted to abut in the plane of the ends of the sections, a link having its ends pivoted to the respective channel members of the pair whereby the sections may be swung from alignment into spaced parallel relation, and means on the members for drawing the members into abutting contact and for maintaining same in such position, additional webs secured in said channel members between the flanges thereof and spaced from and parallel with the webs of the channels; said additional webs being adapted to abut in the plane of the ends of the sections; said links entering the spaces between the webs of the channels and the additional webs; pivot pins transfixing the links and passing through the channel webs and

additional webs; and the flanges of the channels adjacent the links being slotted to permit swinging movement of the links.

3. A ski comprising front and rear runner sections having their adjacent ends adapted to abut in a transverse plane disposed at an angle to the plane of the aligned sections; hinge units connecting the sections; each unit including a pair of channel members secured to the respective sides of the sections and adapted to abut in the plane of the ends of the sections, a link having its ends pivoted to the respective channel members of the pair whereby the sections may be swung from alignment into spaced parallel relation, and means on the members for drawing the members into abutting contact and for maintaining same in such position, additional webs secured in said channel members between the flanges thereof and spaced from and parallel with the webs of the channels; said additional webs being adapted to abut in the plane of the ends of the sections; said links entering the spaces between the webs of the channels and the additional webs and disposed substantially parallel with and adjacent to the flanges of the channel members when aligned; pivot pins transfixing the links and passing through the channel webs and additional webs; and the bottom flanges of the channels being slotted to permit swinging movement of the links.

4. A ski comprising front and rear runner sections having their adjacent ends adapted to abut in a transverse plane disposed at an angle to the plane of the aligned sections; hinge units connecting the sections; each unit including a pair of channel members secured to the respective sides of the sections and adapted to abut in the plane of the ends of the sections, a link having its ends pivoted to the respective channel members of the pair whereby the sections may be swung from alignment into spaced parallel relation, and means on the members for drawing the members into abutting contact and for maintaining same in such position, additional webs secured in said channel members between the flanges thereof and spaced from and parallel with the webs of the channels; said additional webs being adapted to abut in the plane of the ends of the sections; said links entering the spaces between the webs of the channels and the additional webs and disposed substantially parallel with and adjacent to the bottom flanges of the channel members when aligned; pivot pins transfixing the links and passing through the channel webs and additional webs; the bottom flanges of the channels being slotted to permit swinging movement of the links; and aligning tongues secured in the spaces between the channel webs and additional webs of one channel of each pair and disposed adjacent the upper flanges thereof and adapted to enter the corresponding spaces in the other channels when the channels are aligned.

5. A ski comprising front and rear runner sections having their adjacent ends adapted to abut in a transverse plane disposed at an angle to the plane of the aligned sections; hinge units connecting the sections; each unit including a pair of channel members secured to the respective sides of the sections and adapted to abut in the plane of the ends of the sections, a link having its ends pivoted to the respective channel members of the pair whereby the sections may be swung from alignment into spaced parallel relation, and means on the members for draw-

ing the members into abutting contact and for maintaining same in such position, said drawing and locking means comprising a slot in the upper flange of one channel of each pair; a bolt rigidly secured to the web of the other channel and extending above the upper flange thereof, the axis of the bolt crossing the beveled end of said channel; said bolt entering the slot in the first channel when the channels are aligned; and a wing nut on the bolt adapted to engage the top of the slotted flange.

6. A ski comprising front and rear runner sections having their adjacent ends adapted to abut in a transverse plane disposed at substantially 60° to the plane of the aligned sections; hinge units connecting the sections; each unit including a pair of channel members secured to the respective sides of the sections and adapted to abut in the plane of the ends of the sections, a link having its ends pivoted to the respective channel members of the pair whereby the sections may be swung from alignment into spaced parallel relation; a slot in the upper flange of one channel; a projection rigidly secured to the web of the other channel and disposed substantially at right angles to said link, said projection crossing the beveled end of said other channel and extending above the upper flange of said other channel, and being adapted to enter the slot in the first channel when the channels are aligned; and means on the projection adapted to engage the top of said slotted flange for drawing the channels into abutting contact and for locking the channels in such position.

7. In a ski as set forth in claim 6, additional webs secured in said channel members between the flanges thereof and spaced from and parallel with the webs of the channels; said additional webs being adapted to abut in the plane of the ends of the sections; said links entering the spaces between the webs of the channels and the additional webs; pivot pins transfixing the links and passing through the channels webs and additional webs; and the flanges of the channels adjacent the links being slotted to permit swinging movement of the links.

8. In a ski as set forth in claim 6, additional webs secured in said channel members between the flanges thereof and spaced from and parallel with the webs of the channels; said additional webs being adapted to abut in the plane of the ends of the sections; said links entering the spaces between the webs of the channels and the additional webs and disposed substantially parallel with and adjacent to the flanges of the channel members when aligned; pivot pins transfixing the links and passing through the channel webs and additional webs; and the bottom flanges of the channels being slotted to permit swinging movement of the links.

9. In a ski as set forth in claim 6, additional webs secured in said channel members between the flanges thereof and spaced from and parallel with the webs of the channels; said additional webs being adapted to abut in the plane of the ends of the sections; said links entering the spaces between the webs of the channels and the additional webs and disposed substantially parallel with and adjacent to the bottom flanges of the channel members when aligned; pivot pins transfixing the links and passing through the channel webs and additional webs; the bottom flanges of the channels being slotted to permit swinging movement of the links; and aligning tongues secured in the spaces between the chan-

nel webs and additional webs of one channel of each pair and disposed adjacent the upper flanges thereof and adapted to enter the corresponding spaces in the other channels when the channels are aligned.

10. A ski comprising runner sections having their adjacent ends adapted to abut in a transverse plane disposed at an angle to the plane of the aligned sections; hinge units connecting the sections, each unit including a pair of members secured to the respective sides of the sections and adapted to abut in the plane of the ends of the sections; a link having its ends pivoted to the respective members of the pair whereby the sections may be swung from alignment into spaced parallel relation; the upper corner of the abutting end of the overlying member having a slot therein; and a projection carried by the other member adapted to cross the beveled end thereof and to extend above the upper face of said slotted member and to enter the slot when the members are aligned; and means on said projection adapted to engage the upper face of said slotted member to lock same in abutting relation.

11. A ski comprising front and rear runner sections having their adjacent ends adapted to abut in a transverse plane disposed at an angle to the plane of the aligned sections; hinge units connecting the sections, each unit including a pair of channel members secured to the respective sides of the sections and adapted to abut in the plane of the ends of the sections, a link having its ends pivoted to the respective channel members of the pair whereby the sections may be swung from alignment into spaced parallel relation, the outer corner of the upper flange of the abutting end of the overlying channel having a slot therein; a projection carried by the other channel adapted to cross the beveled end thereof and to extend above the upper flange

thereof and to enter the slot when the channels are aligned; and means on said projection adapted to engage the upper flange of said slotted channel for drawing the channels into abutting contact and for maintaining same in such position.

12. A ski comprising front and rear runner sections having their adjacent ends adapted to abut in a transverse plane disposed at an angle to the plane of the aligned sections; hinge units connecting the sections, each unit including a pair of channel members secured to the respective sides of the sections and adapted to abut in the plane of the ends of the sections; additional webs secured in said channel members between the flanges thereof and spaced from and parallel with the webs of the channels; said additional webs being adapted to abut in the plane of the ends of the sections; a link having its ends pivoted to the respective channel members of the pair whereby the sections may be swung from alignment into spaced parallel relation, said link entering the spaces between the webs of the channels and the additional webs; pivot pins transfixing the link and passing through the channel webs and additional webs; the flanges of the channels adjacent the links being recessed to permit swinging movement of the links; the upper corner of the abutting end of the overlying channel member having a slot therein, and a projection carried by the other channel adapted to cross the beveled end thereof and to extend above the upper flange of the slotted channel and to enter the slot when the channels are aligned; and means on said projection adapted to engage the upper flange of the slotted channel for drawing the members into abutting contact and for maintaining same in such position.
